UNITED STATES PATENT OFFICE

KAZIMER MARCINAUSKAS, OF CHICAGO, ILLINOIS

ADJUSTABLE SCAFFOLD

Application filed January 28, 1929. Serial No. 335,544.

- This invention relates to an adjustable scaffold adapted to be assembled and mounted in position against the side of a wall or building to facilitate painting of the wall or making of repairs or the like, said scaffold embracing frames or cages adapted to be placed against the surface of the wall and supported in position by means of adjustable braces with said cages having uprights 5 on the upper ends of which blocks and tackles are mounted and connected to a cross-beam to facilitate raising the cross-beam into an elevated position to afford a suitable support for a roller carriage on which a saddle or seat 10 is suspended by means of ropes and pulleys to permit the saddle to be raised or lowered so that access to different portions of the wall or building on which the scaffold is engaged may be readily had.
- It is an object of this invention to provide an adjustable scaffold adapted to be braced in position against the side of a building and having an adjustable saddle which may be raised or lowered or moved sidewardly in either direction to permit a person sitting in the saddle to have access to all portions of the wall of the building against which the scaffold is placed.
- It is also an object of this invention to provide an adjustable scaffold adapted to be removably placed in position against the outer wall of a building with said scaffold having a cross-beam adapted to be raised in position to support a roller carriage on which an adjustable saddle is engaged to permit a person to be moved into different positions adjacent the wall of the building to facilitate painting or repairing of different parts thereof.
- It is a further object of this invention to provide an adjustable scaffold comprising a pair of cages or frames which are adapted to be seated against a wall and supported in position by means of adjustable or extensible braces so that a cross-beam may be raised into a predetermined position and held in said position to support an adjustable saddle in a position permitting a person to have ready access to different portions of the wall 40 45 50
- embraced within the confines of the adjustable scaffold.
- It is furthermore an object of this invention to provide an adjustable scaffold consisting of adjustable uprights having cages 55 forming a part thereof adapted to seat against the outer surface of a wall with said uprights being provided with blocks and tackles to facilitate raising of a cross-beam into a predetermined elevated position to 60 support a suspended saddle or seat in a position to permit the saddle to be raised or lowered or moved transversely of the wall to permit painting or repairs to be made to different portions of the wall between the adjustable uprights and below the cross-beam on which the saddle is supported.
- It is an important object of this invention to provide an adjustable scaffold adapted to be removably placed against the side of 70 a building and having a cross-beam which may be raised or lowered to properly position a traveling carriage so that an adjustable saddle supported by said carriage may be moved into different positions within the 75 confines of the members comprising the adjustable scaffold to afford ready access to different portions of the wall against which the scaffold is placed so that the wall may be painted or repairs may be made to all 80 parts of the wall.
- Other and further important objects of this invention will be apparent from the disclosures in the specification and the accompanying drawings.
- This invention (in a preferred form) is 85 illustrated in the drawings and hereinafter more fully described.
- On the drawings:
- Figure 1 illustrates a fragmentary side elevation of a wall of a building having engaged thereagainst an improved adjustable scaffold embodying the principles of this invention.
- Figure 2 is an enlarged top plan view of 90 one of the side cages or frames taken on line II-II of Figure 1.
- Figure 3 is a reduced side elevational view taken on line III-III of Figure 2.
- Figure 4 is a vertical sectional view taken 100

on line IV—IV of Figure 2 illustrating a portion of a brace member in position and also showing a portion of the saddle supporting beam seated in place.

Figure 5 is an enlarged side elevation of the saddle supporting carriage engaged on a fragmentary portion of the beam supporting the same.

Figure 6 is an enlarged transverse section taken on line VI—VI of Figure 5.

Figure 7 is a fragmentary side view of the middle portion of one of the adjustable brace members used to support one of the cages or frames of the scaffold in position.

Figure 8 illustrates a fragmentary side view of a modified form of adjustable brace member for use in supporting the cages or frames of the scaffold in place.

As shown on the drawings:

The reference numeral 1 indicates the wall of a building which is either to be painted or repaired and against which an improved adjustable scaffold embodying the principles of this invention is engaged. The adjustable scaffold comprises a pair of cages or frames each embracing a back 2 and two converging side walls 3 rigidly connected at their front ends to an upright 4 which is braced in position by means of transverse slotted frames or brackets 5 which extend rearwardly from the upright 4 and are secured at their rear ends to cross members forming part of the back 2 of the cage. Formed on the upper portion of the back 2 of the cage is a socket or pocket 6 for the reception of the upper end of a collapsible brace comprising a plurality of brace members or poles 7 and 8 which are connected together by means of a hinge 9 or other suitable means to permit the brace members to be collapsed when not in use. Engaged on the brace rods or members 7 is a loop connector or clamp member 10 which is adapted to be engaged over the end of the brace bar 8 lying adjacent the brace bar 7 to hold the brace members rigidly clamped together in the extended position illustrated in Figures 1 and 7.

The upper end of the top brace member 7 is projected through the slot of the brace 5 forming part of a cage with the upper end of the brace member 7 projected into or seats in the socket 6 formed at the upper portion of the rear wall of the cage as illustrated in Figure 4. By this means the extended brace has the lower end thereof seated upon the ground and the upper end engaged in the cage to hold the cage in a predetermined elevated position to permit the back of the rear wall 2 to seat flatly against the surface of the wall of the building 1.

Rigidly clamped by means of brace rings 11 or the like on the upper end of the front upright 4 of each cage is an extension shaft or pole 12 provided with a notch 13 in the front side of the upper end thereof to afford

a seat or pocket for one end of a transversely positioned carriage supporting beam or bar 14.

The end of the cross-beam 14 has pivotally supported thereon by means of bolts 15 U-straps or hangers 16. Connected to the hangers 16 are ropes 17 which are engaged through blocks 18 which are supported on the upper ends of the vertical extension bars 12 and form a block and tackle arrangement whereby the cross-beam 14 may be raised and lowered by means of the ropes 17. When the cross-beam 14 is raised to its uppermost position by means of the ropes 17, said cross bar is adapted to seat in the notches or pockets 13 of the upright extension bars 12 as illustrated in Figure 4. The cross-beam 14 has stop blocks or cleats 34 secured to the front side thereof to hold the cross-beam 14 against shifting longitudinally or transversely of the uprights 12.

Secured on the front faces of the uprights 12 adjacent the notches 13 are brackets 35 adapted to form pockets for the reception of the cross-beam 14. The brackets 35 hold the cross-beam in place seated in the notches 13. The cross-beam 14 is adapted to be raised by means of the ropes 17 to a point above the brackets 35, after which the cross-beam moves toward the uprights 12 and is lowered to seat behind the brackets 35 as illustrated in Figure 4.

Pivots mounted on the sides of each upright 12 is a fulcrumed release guide or arm 36 to one end of which a release rope or trip cable 37 is attached. When it is desired to lower the cross-beam, it is first raised out of the sockets 13 by means of the ropes 17 to clear the upper ends of the brackets 35. The release ropes 37 are now pulled to swing the guide arms 36 from the full line position of Figure 4 into the inclined dotted line position to close the sockets. The cross-beam 14 is now lowered and slides outwardly over the inclined guide arms 36 and over the brackets 35, thereby permitting the cross-beam to clear the sockets and be lowered to the ground.

Movably supported upon the cross-beam 14 is a carriage 19 which straddles the cross-beam 14 and is provided with a pair of upper supporting rollers 20 which rotatably track upon the upper edge of the cross-beam 14. Rotatably supported in the lower corners of the carriage 19 are small and large pulley wheels 21 and 22 respectively (Fig. 6). Rotatably supported in an opening in each of the upright members 23 of the carriage 19 is a guide roller 24. The guide rollers 24 are so positioned that they track on the side surfaces of the cross-beam 14 thereby affording an arrangement whereby the carriage 19 may be easily run back and forth on the cross-beam.

Engaged over the two large pulley wheels 120

22 of the carriage and passing through a block 25 is a rope or cable 26. One end of the rope or cable 26 is connected to one arm 27 of a saddle or chair 28, the other arm 29 of which is hung on a hook 30 carried by the block 25 as illustrated in Figure 1. A person seated in the saddle or seat 28 is thus permitted to raise himself by pulling on the rope or cable 26 thereby causing the saddle to be raised or lowered as desired so that different portions of the wall 1 may be conveniently reached.

Figure 8 illustrates a modified form of extensible brace adapted for use in place of the brace illustrated in Figure 7 and comprising a plurality of overlapping bars or poles 31, the overlapped portions of which are rigidly connected together by means of clamps or loop members 32 which are pivotally supported on one of said brace bars 31.

When the adjustable scaffold is to be used, a pair of cages or frames 2-4 are adapted to be raised on the upper end of a pair of braces 7-8 with the lower ends of the braces seated against the ground so that the cages or frames may be elevated a desired distance with the flat backs 2 of the triangular cages resting against the outer surface of the wall 1. A horizontal brace beam or sill 33 projects through the lower portions of the cages or frames 2-4 and rests on the lower bracket 5 of the cages as illustrated in Figure 1 and are secured to said cages to hold the same properly spaced one from the other. By manipulating the ropes or cables 17, the cross-beam 14 is adapted to be raised to seat in the brackets 35 so that the carriage 19 is raised to a desired height with the cross-beam 14. With the cross-beam raised to seat in the brackets 35 the saddle 28 is adapted to be raised off of the ground by proper manipulation of the cable or rope 26. The cross-beam 14 may now be raised above the level of the two supporting cages until said beam passes the brackets 35. The cross-beam 14 is now lowered to permit the cross-beam to pass the released guide arms 36 and seat in said notches or sockets 13 behind the brackets 35 to properly support the carriage at the desired elevation. A person sitting in the saddle 28 may thus elevate or lower himself and by using his feet on the wall may move the carriage transversely so that the carriage will roll on the cross-beam 14. In this manner a person seated in the saddle 28 may cover all portions of the building wall 1 within the confines of the adjustable scaffold so that the wall may either be painted or repaired as the case may require.

It will thus be noted that quite a large area of a wall may be conveniently covered with a single positioning of the adjustable scaffold. If desired, the extensible braces 7-8 which support the cages or frames in position, may

be of the type illustrated in Figures 7 and 8, or if preferred, may be of a telescoping type or any other suitable form to satisfactorily brace the cages in place against a wall.

Attention is directed to the fact that the improved adjustable scaffold may be conveniently adapted for use at elevations above the second, third or fourth floors of a building. By omitting the brace members, the cages 2-4 may be supported on the window sills of the windows of a building with the rear portions 2 facing inwardly and with the uprights 4 and extensions 12 projecting upwardly on the outside of the building. The cages may be braced in position seated upon the window sills by means of cross bars projecting transversely through the rear portions of the cages above the bracket members 5 to hold the cages properly seated in position. By this means a pair of cages may be mounted in two different windows with the uprights positioned in a convenient location to permit the cross-beam 14 to be raised in position and seated in the pockets 13 thereby conveniently supporting the saddle 28 in a suspended position at any desired elevation above the ground.

It will, of course, be understood that many changes may be made and that numerous details of construction may be varied through a wide range without departing from the principles of this invention and it is therefore not purposed limiting the patent granted hereon otherwise than necessitated by the scope of the appended claims.

I claim as my invention:

1. An adjustable scaffold comprising a pair of cages, adjustable brace members for independently supporting the same in position against a wall, extension members on said cages, block and tackle mechanisms supported on said extension members, a cross-beam supported by said block and tackle mechanisms, a carriage movably supported on said cross-beam, a saddle, and means adjustably supporting said saddle from said carriage.

2. An adjustable scaffold comprising a pair of frames, adjustable brace members projecting upwardly through the bottoms of said frames for supporting the same against a wall, a cross-beam, means for supporting said cross-beam on said frames, a carriage movably mounted on said cross-beam and a saddle adjustably supported on said carriage.

3. An adjustable scaffold comprising a pair of adjustable upright mechanisms adapted to be engaged against a wall, extensions secured on said mechanisms, a cross-beam, means for adjustably supporting said cross-beam on said extensions, a carriage movably supported on said cross-beam, and a saddle adjustably supported from said carriage.

4. An adjustable scaffold comprising a pair of frames, adjustable brace means for sup-

porting the same against a building, a brace member connecting said frames to hold the same in spaced relation, extensions on said frames, brackets thereon, a cross-beam, means on said extensions for elevating said cross-beam into a predetermined position to seat in said brackets, and a saddle mechanism adjustably suspended from said cross-beam.

5. An adjustable scaffold comprising a pair of cages, extensible brace members engaged in said cages to hold the same supported at an elevated position above the ground and against a wall of a building, extensions on said cages, block and tackle means supported on said extensions, a cross-beam supported on said block and tackle means, a roller carriage movably engaged on said cross-beam, rope and pulley mechanisms carried by said carriage and a saddle supported by said rope and pulley mechanisms.

6. An adjustable scaffold comprising a plurality of cages adapted to be engaged against a wall of a building, adjustable brace members for independently supporting each of the cages in position, a cross-beam, bracket members on said cages, means on said cages for raising the cross-beam to a predetermined position to permit the same to seat on said cages behind said bracket members, a roller carriage on said cross-beam, and a saddle mechanism adjustably carried by said roller carriage.

7. An adjustable scaffold comprising a pair of cages, adjustable brace means for supporting the same against a wall of a building, an adjustable cross-beam connecting said cages, a carriage movably mounted on said cross-beam and a saddle adjustably supported on said carriage.

8. An adjustable scaffold comprising a cross-beam, adjustable brace mechanisms adapted to be supported on the ground and have contact with a wall of a building, means on said brace mechanisms for supporting the cross-beam in a predetermined elevated position, fulcrumed members on said brace mechanisms to facilitate lowering of the cross-beam, a movable carriage on said cross-beam, a saddle, and adjustable means connecting said saddle with said carriage to permit the saddle to be elevated and lowered to afford ready access to different portions of the wall against which the scaffold is engaged.

9. An adjustable scaffold comprising a pair of cages adapted to be seated against a wall, adjustable braces for supporting the cages in position, a brace member connecting said cages one to the other, notched extensions on said cages, brackets secured on said extensions, block and tackle means supported on said extensions, a cross-beam supported by said block and tackle means adapted to be lowered into said brackets, a carriage mov-

ably mounted on said cross-beam, a saddle, pulley wheels mounted on said carriage, a rope engaged on said pulley wheels and connected to said saddle to permit the saddle to be raised and lowered with respect to said cross-beam to afford ready access to different portions of the wall on which the scaffold is engaged, members on said extensions, and means for operating said members to facilitate lowering of the cross-beam.

10. An adjustable scaffold comprising a pair of cages, uprights forming a part thereof, adjustable brace members engaged in said cages to hold the same supported at a predetermined distance above the ground and seated against a wall of a building, a cross-beam, means on said uprights for raising the cross-beam to a predetermined position to permit the same to be supported on said uprights, brackets on said uprights to hold the cross-beam in its elevated position, a saddle adjustably supported from said cross-beam and adapted to be moved both vertically and horizontally with respect to the wall to afford access to different portions of the wall, trip members fulcrumed on said uprights, and means for actuating said trip members when the cross-beam is raised to position said trip members to guide the cross-beam downwardly past said hooks when it is desired to lower said cross-beam.

11. An adjustable scaffold comprising a pair of cages, means for connecting the same, brace members for supporting the cages against a wall at a predetermined distance from the ground, a cross-beam, stop blocks on said cross-beam, means on said cages for adjustably supporting the cross-beam at a predetermined elevation from the ground, fulcrumed means on said cages permitting release and lowering of the cross-beam, a supporting member movably mounted on said cross-beam, a saddle thereon for carrying a person, and means for adjustably supporting said saddle from said movably supporting member to permit the saddle to be adjusted with respect to the wall on which the scaffold is mounted.

In testimony whereof I have hereunto subscribed my name at Chicago, Cook County, Illinois.

KAZIMER MARCINAUSKAS.
